DESIGN FOR A CHEST OR SIMILAR ARTICLE

Anthony J. Buckner, Jackson Heights, N. Y., assignor to Grosfeld House, Inc., New York, N. Y., a corporation of New York

Application April 2, 1942, Serial No. 106,434

Term of patent 3½ years

To all whom it may concern:

Be it known that I, Anthony J. Buckner, a citizen of the United States of America, residing in Jackson Heights, county of Queens and State of New York, have invented a new, original, and ornamental Design for a Chest or Similar Article, of which the following is a specification, reference being had to the accompanying drawing, forming part thereof, wherein:

Fig. 1 is a front perspective view of a chest or similar article, showing my new design, it being understood that the end not shown is identical with the end illustrated; and

Fig. 2 is a top plan view thereof, on a reduced scale.

I claim:

The ornamental design for a chest or similar article, substantially as shown and described.

ANTHONY J. BUCKNER.
